Term of patent 14 years

(Cl. D63—1)

FIG.1.

FIG.2.

FIG.3.

Fig. 1 is a perspective view of a boring machine showing my new design.

Fig. 2 is a front view of the machine of Fig. 1 on a slightly smaller scale.

Fig. 3 is a side view of the machine of Fig. 1 also on a slightly smaller scale. The other side of the machine is similar to the side shown and the top is substantially plain.

I claim:

The ornamental design for a precision boring machine, substantially as shown and described.
